COMBINED TABLE AND CONVERTIBLE SOFA BED

Ewald A. Kamp and Chester A. Pink, Chicago, Ill., assignors to The Englander Company, Inc., Chicago, Ill.,
a corporation of Delaware

Filed Mar. 24, 1961, Ser. No. 64,465

Term of patent 14 years

(Cl. D5—4)

FIG. 1 is a front perspective view of a combined table and convertible sofa bed embodying our new design, the structure being shown as it would appear for use in the daytime as a couch;

FIG. 2 is the front perspective view of a combined table and convertible sofa bed of FIG. 1 but showing the structure as it would appear for use in the nighttime as a bed;

FIG. 3 is a rear perspective view of the showing of FIG. 1;

FIG. 4 is a left side elevational view of the showing of FIG. 1; and

FIG. 5 is a right side elevational view of the showing of FIG. 1.

The dominant features of our design reside in those portions shown in full lines on the drawing.

We claim:

The ornamental design for a combined table and convertible sofa bed, substantially as shown and described.
